UNITED STATES PATENT OFFICE.

CORNELIUS J. RUKENBROD, OF PRINCETON, NEW JERSEY, ASSIGNOR TO THE ELECTRIC PORCELAIN AND MANUFACTURING COMPANY, OF TRENTON, NEW JERSEY, A CORPORATION OF NEW JERSEY.

MEANS FOR SECURING VITREOUS ARTICLES IN PLACE.

Application filed May 4, 1926. Serial No. 106,775.

The principal object of my invention is to provide means for securing vitreous articles to a base structure in such a manner that the securing means shall not be visible when viewing the said vitreous article.

Another object of my invention is to provide a handle structure, such as those employed on oven doors of gas ranges and the like, the handle structure comprising a pair of pedestals constructed entirely of vitreous substance such as porcelain or like material, and a hand grip extending between the said pair of pedestals and being composed of a like substance such as that used in the construction of the pedestals and to provide securing means for the handle, such as that described above, which will not be visible from the outside of the oven door to which the handle is secured.

Other advantages and details of the invention will be set forth more fully hereinafter, reference being had to the accompanying drawings, of which:

Fig. 1 is a plan view of my improved handle;

Fig. 2 is a side elevation, partly in section along the line 2—2 of Fig. 1;

Fig. 3 is a sectional elevation taken along the line 3—3 of Fig. 2;

Fig. 4 is a perspective view of the locking element illustrated in Figs. 2 and 3;

Fig. 5 is a side elevation, partly in section, of a modified form of the invention;

Fig. 6 is a sectional elevation, taken along the line 6—6 of Fig. 5;

Fig. 7 is a side elevation, partly in section, of another modified form of the invention; and

Fig. 8 is a sectional elevation, taken along the line 8—8 of Fig. 7.

Prior to the conception of my invention, it had been the practice in the manufacture and installation of oven door handles to form the pedestal sections, of the handle, of cast iron or other similar material, and to secure the pedestals to the oven door by means of screws, passing through the frame of said door and being tapped into the body of the pedestal, no practical means being known to the trade for securing pedestals, constructed of vitreous material, to the oven door.

Referring to the drawings, I have illustrated a base structure 1 which, in the present instance, represents a gas oven door as above referred to. Mounted upon said base structure is a pair of pedestals 2, 2 composed of vitreous material, in the present instance glazed porcelain.

Extending between the pedestals 2, 2 is a hand grip 3 provided at each end with a cylindrical projection 4 adapted to extend into a cavity 5 transversely disposed in the head 6 of each of the pedestals 2. Each of the projections 4 is provided with a pair of oppositely disposed rectangular cavities 7. A cylindrical opening 8 is provided in each of the extensions 4, and communicates with the oppositely disposed rectangular cavities 7, 7 therein. Within each cylindrical opening 8, I provide a locking element in the form of an internally threaded sleeve 9 having at one of its ends a rectangular flange 10 adapted to fit within the outermost of the rectangular cavities 7 in each grip extension 4. Each of the pedestals 2 is provided with a longitudinally extending opening 11. The base structure 1 is provided with an opening 12 axially aligned with the opening 11 in each of the pedestals 2. A securing element 13 in the form of a countersunk screw is adapted to pass through each opening 12 in the base structure; through the longitudinal opening 11 in the respective pedestal, and to engage the internal threads of the sleeve 9, within the respective projection 4 of the hand grip 3.

In assembling the handle structure, illustrated in Figs. 1 to 4 inclusive, the locking elements 9 are placed within the openings 7—8 in the projections 4, at each end of the hand grip 3. One of the pedestals 2 is placed upon each of the projections 4 and the assembled handle is placed in a position upon the base structure 1, to be secured thereto. A securing element 13 is then passed through each of the openings 12, in the said base structure; through the longitudinal opening 11 in the respective pedestal, and into the threaded opening of the locking element 9, and by turning the securing element in a clockwise direction the threads thereof engage the internal threads of the respective

locking element 9, thereby drawing the projection 4 tightly against the side wall of the cavity 5 in the pedestal which in turn draws the pedestal structure tightly against the base structure, thereby securing the handle in place and preventing any rattling of the handle on the base structure.

As shown in Fig. 5, the same structure as illustrated in Figs. 1, 2 and 3 obtains, with the exception that the locking element is not provided with an extended sleeve as shown in Fig. 2, being merely a rectangular nut 9^a adapted to a rectangular cavity 7^a in the extension 4, the transverse opening 8^a in the said extension being reduced to a point sufficient to permit the passage of the securing element 13 therethrough.

The process of assembling in this case is identical with that described in reference to the structure illustrated in Figs. 2 and 3.

In Figs. 7 and 8, the cavity 5 of each of the pedestals 2 is provided with a rectangular groove 14 in its side wall adjacent the base structure 1. In this embodiment of the invention, the locking element 9^b is in the form of a rectangular internally threaded nut, which is adapted to occupy a position within the groove 14. When assembling this arrangement of elements a locking element 9^b is placed in each of the pedestals 2, within the groove 14. The projection 4^b of the hand grip 3^b is placed within the cavity 5 of the pedestal 2 and is provided with a pair of oppositely disposed cavities 7^b, one of which is adapted to align with the securing locking element 9^b. The securing element 13^b is passed through the opening 12 in the base structure 1 as above described, and thence through the longitudinal opening 11 in the pedestal. The threaded end 15 of the securing element 13^b engages the internal threads of the locking element 9^b passing therethrough and through the transverse opening 8^b in the projection 4^b as illustrated in Figs. 7 and 8.

It will be understood that, while my invention is particularly adaptable to the securing of all vitreous handles to structures such as oven doors and the like, such embodiments being illustrated in the accompanying drawings, the illustrations are not to be construed as limiting the scope of the invention, as my invention may be adapted to other vitreous articles, such as bathroom fixtures and, therefore, only such limitations should be placed thereon as are prescribed in the appended claims or dictated by the prior art of record.

I claim:

1. In means for securing vitreous handles to oven doors and the like, said handle comprising a pair of spaced single piece pedestals and a single piece hand grip supported thereby, each pedestal having but one cavity

formed therein, which extends transversely of the pedestal and inwardly from one side only thereof, and an opening extending longitudinally through the pedestal from the base thereof to the bottom side of the said transverse cavity; said hand grip being provided with a projection on each of its ends extending into the transverse cavity of the respective pedestal and having an opening adapted to be aligned with the longitudinal opening in the pedestal; a threaded locking element adapted to be placed in the opening in said hand grip, prior to the placing of the hand grip projection into the transverse cavity of the pedestal; and a securing screw adapted to be passed through an aperture in the oven door, through the longitudinal opening in the pedestal and engaging the threads of the locking element in the hand grip.

2. In means for securing vitreous handles to oven doors and the like, said handle comprising a pair of spaced single piece pedestals and a single piece hand grip supported thereby, each pedestal having but one cavity formed therein, which extends transversely of the pedestal and inwardly from one side only thereof, and an opening extending longitudinally through the pedestal from the base thereof to the bottom side of the said transverse cavity; said hand grip being provided with a projection on each of its ends extending into the transverse cavity of the respective pedestal and having an opening adapted to be aligned with the longitudinal opening in the pedestal; a threaded locking element adapted to be placed in the opening in said hand grip, prior to the placing of the hand grip projection into the transverse cavity of the pedestal; a securing screw adapted to be passed through an aperture in the oven door, through the longitudinal opening in the pedestal and engaging the threads of the locking element in the hand grip; and means for preventing the rotation of said locking element in said hand grip projection.

3. In means for securing vitreous handles to oven doors and the like, said handle comprising a pair of spaced single piece pedestals and a single piece hand grip supported thereby, each pedestal having but one cavity formed therein, which extends transversely of the pedestal and inwardly from one side only thereof, and an opening extending longitudinally through the pedestal from the base thereof to the bottom side of the said transverse cavity; said hand grip being provided with a projection on each of its ends extending into the transverse cavity of the respective pedestal and having an opening adapted to be aligned with the longitudinal opening in the pedestal; a threaded locking element adapted to be placed in the opening

in said hand grip, prior to the placing of the hand grip projection into the transverse cavity of the pedestal; a securing screw adapted to be passed through an aperture in the oven door, through the longitudinal opening in the pedestal and engaging the threads of the locking element in the hand grip; and means

for preventing the rotation of said locking element in said hand grip projection, comprising a flat sided head on said locking element adapted to be located in a flat sided cavity formed in said hand grip projection around the said opening therein. 10

CORNELIUS J. RUKENBROD.
